BOTTLE CLOSURE

Joseph B. Biederman, Cincinnati, Ohio

Application June 8, 1953, Serial No. 360,225

2 Claims. (Cl. 215—86)

This invention relates to a removable closure for a bottle and more particularly to a sealing closure for a bottle containing a carbonated beverage or the like.

An object of this invention is to provide a removable and reusable closure for a bottle which forms a firm double seal to prevent escape of carbonation.

A further object of this invention is to provide a closure member having a plug which fits into the neck of a bottle and which is forced firmly against the inside of the neck by pressure inside the bottle.

A further object of this invention is to provide a closure member of this type having a plug of elastomeric material provided with a cylindrical skirt portion which is firmly held against the inside of the neck of a bottle by pressure inside the bottle.

A further object of this invention is to provide a closure member of this type having a retainer member hinged to the plug, which retainer member engages the bead at the mouth of the bottle to hold the plug inside the neck of the bottle.

From the following description and the accompanying drawing, the above and other objects and features of the invention will be apparent to those having ordinary skill in the art to which it pertains.

In the drawing:

Figure 1 is a perspective view showing a bottle provided with a closure member constructed in accordance with an embodiment of this invention;

Fig. 2 is a view in section taken along a line II—II in Fig. 1;

Fig. 3 is an exploded view showing the parts of the closure member;

Fig. 4 is a view in section taken along a line IV—IV in Fig. 3; and

Fig. 5 is a view partly in side elevation, and partly in section showing a bottle having a closure member constructed in accordance with another embodiment of the invention.

In the following detailed description and the drawing, like reference characters indicate like parts.

The closure member shown in Figs. 1—4 inclusive includes a one-piece body 10, a retainer member 12, a pivot pin 13 and a pin-retaining disk 14.

The body 10 may be formed of rubber or other suitable elastomeric material. The body includes a cylindrical cap portion 16 which overlies the mouth of a bottle 17, as shown in Fig. 2, and a cylindrical plug 18 which fits into the bottle through the mouth thereof. The inner end of the plug is concave as indicated at 19 so that an annular or cylindrical skirt 21 is formed. The cylindrical portion 21 is adapted to be deformed or spread by pressure inside the bottle to cause the cylindrical inner end portion of the plug to firmly engage the inside surface of the neck of the bottle 17. As shown, the plug is provided with an annular groove 22 between the inner end portion of the plug and the cap to allow the cylindrical inner end portion to flex sufficiently to provide a gas-tight seal.

The upper end of the cap portion is provided with a

2

counterbore 23 surrounded by an annular rim 24. A slot 26 (see Fig. 3) is formed in rim 24 and across a diameter of the cap portion to receive the pivot pin 13, as shown in Fig. 2. The pivot pin 13 is held in place in the slot 26 by means of the plate 14. The inner end of the bore 23 is undercut as at 28, in Fig. 2, to receive and hold the edge of the plate 14, whereby the plate 14 in turn, holds the pin in the slot. The plate may be decorated with any appropriate indicia, such as a trademark, slogan, or the like.

10 The retainer member 12 is pivotally supported on the pin 13. As shown, the retainer member 12 is substantially half circular in cross section or U-shape, and is provided with openings 29 and 31 through which the ends of the pin 13 project. A flange 32 is formed on the edge 15 of the retainer member 12 remote from openings 29 and 31. As shown in Figs. 1 and 2, the flange 32 swings beneath the bead 33 at the mouth of the bottle so that the retainer member holds the body firmly in position, as shown in Fig. 2. The upper edge of member 12 is provided with a flange 33 for limiting the swinging or turning 20 of the body member with respect to the retainer member 12.

When the closure member is inserted in the mouth of 25 the bottle, as shown in Fig. 2, a double seal is formed, there being a seal between the cap portion 16 and the lip of the bottle, as well between the cylindrical inner end portion of the plug and the inside wall surface of the bottle neck.

30 In Fig. 5 is shown a modified form of the device. The device in Fig. 5 corresponds to the device of the other drawing with the exception that instead of a pivot pin, an elongated member 35 is employed having a pivot pin portion 36 which extends through flanges of a retainer member 37 and through the cap portion of a body 38. 35 One end of the pin portion 36 is integrally formed with an elongated hook or support member 39. The hook member 39 extends away from the closure member and forms a support by means of which the closure member and the bottle may be hung from an appropriate support 40 41 or the like.

45 The bottle closures illustrated in the drawing and described above are subject to structural modification without departing from the spirit and scope of the appended claims.

45 Having described my invention, what I claim as new and desire to secure by Letters Patent is:

1. A removable closure for a bottle having a neck, an open mouth at one end of the neck, and a bead on the outside of the neck spaced from the mouth which comprises a one-piece body of elastomeric material having a plug adapted to be received inside the neck of the bottle and a cap portion for overlying the mouth of the bottle, said plug having an annular groove between the inner end thereof and the cap portion, the inner end portion of the plug being cylindrical and engageable with the inside surface of the neck of the bottle, the surface of the inner end of the plug being concave, thereby rendering the cylindrical portion deformable by pressure inside the bottle to firmly engage the inner surface of the bottle neck, the cap portion being provided with a diametrically extending slot, a one-piece pivot pin in said slot with ends of the pivot pin projecting on opposite sides of the cap portion, the cap portion being provided with a bore extending on both sides of the slot, an annular rim on the cap portion surrounding the bore, a pin retaining plate received in the bore overlying the pin and engaging the rim to hold the pin in the slot, and a cap retainer member pivotally mounted on said pin, said retainer member having a flange engageable with the bead of the bottle to hold the closure body with the plug inside the neck of the bottle and the cap portion in engagement with the mouth of the bottle.

2. A removable closure for a bottle having a neck, an open mouth at one end of the neck, and a bead on the outside of the neck spaced from the mouth which comprises a one-piece body of elastomeric material having a plug adapted to be received inside the neck of the bottle and a cap portion for overlying the mouth of the bottle, said plug having an annular groove between the inner end thereof and the cap portion, the inner end portion of the plug being cylindrical and engageable with the inside surface of the neck of the bottle, the surface of the inner end of the plug being concave, thereby rendering the cylindrical portion deformable by pressure inside the bottle to firmly engage the inner surface of the bottle neck, the cap portion being provided with a diametrically extending slot, a one-piece pivot pin in said slot with ends of the pivot pin projecting on opposite sides of the cap portion, a hook member integrally formed with one end of the pin and extending away from the body member, the cap

portion being provided with a bore extending on both sides of the slot, an annular rim on the cap portion surrounding the bore, a pin retainer plate in the bore overlying a portion of the pin and engaging the rim to hold the pin in the slot, and a cap retainer member pivotally mounted on said pin, said retainer member having a flange engageable with the bead of the bottle to hold the closure body with the plug inside the neck of the bottle and the cap portion in engagement with the mouth of the bottle.
